2 Sheets-Sheet 2

UNITED STATES PATENT OFFICE

CARL F. FRAUENBERGER, OF FRANKLIN, MASSACHUSETTS, ASSIGNOR TO THOMSON
NATIONAL PRESS CO. INC., A CORPORATION OF DELAWARE

SHEET-PUSH-OFF MECHANISM

Application filed October 25, 1928. Serial No. 314,879.

The object of this invention is to provide improvements in sheet feeding mechanisms for use on cutting, creasing and embossing presses of the type handling relatively large 5 and heavy sheets of cardboard and like material for the manufacture of boxes and receptacles.

Heretofore it has been the practice to separate the top sheet from the pile by means of 10 frictional devices which engage the top sheet and slide it off or push it off the pile to enable suitable gripping devices to seize the leading edge of the sheet and convey it to the press.

It has been found, however, that such frictional 15 separating devices do not always work satisfactorily for several reasons, amongst which may be cited the natural adhesion between the sheets, surface conditions and the like, as well as weight. Where, for instance, 20 heavy sheets of the kinds used for making automobile door panels are to be separated automatically, it is desirable to provide more efficient separating means.

It has been found entirely practicable to 25 separate such and other sheets by means of a push-off mechanism arranged to engage the front edge of the sheet and push it off the pile in a direction towards the press. The main object therefore, of this invention is to provide 30 a sheet push off mechanism adapted to be mounted on an automatic feeder for cutting, creasing and embossing presses, and arranged to engage the edge of the sheet and push it off the pile.

Accordingly the invention is embodied in a 35 sheet push off mechanism arranged and constructed as hereinafter set forth and as illustrated in the accompanying drawings in which

Fig. 1 is a side view of a sheet push off mechanism embodying the invention with parts in section and showing the mechanism in retracted normal position.

Fig. 2 is a similar view showing the mechanism 40 in position when the top sheet has been pushed off the pile and with parts broken away.

Fig. 3 is a plan view.

Fig. 4 is a sectional view on line 4-4 of 45 Figure 1.

Fig. 5 is a sectional view on line 5-5 of Figure 1.

Fig. 6 is a sectional view on line 6-6 of Figure 1.

Fig. 7 is a detail view of the sheet engaging member. 55

The invention is more particularly directed towards improvements in sheet feeding mechanisms of the type disclosed in the application for patent filed November 16, 1927, 60 Serial Number 233,643. With respect to the supporting means for the device reference is therefore made to the said application.

Referring to the drawings the reference numeral 8 denotes the pile of sheets which is 65 usually supported on a pile elevator, indicated at 9, so that as the top sheet is removed the pile is elevated to maintain the desired level in an obvious and well understood manner in the art. The sheet feeding device further includes certain fixed supporting members which are located above the pile of the sheet transversely thereof. Some of said members are used for the support of the herein disclosed push-off mechanism. Thus, the 70 reference numerals 11, 11 denote two fixed cross bars and 12 a fixed shaft which are part of the device to which the push-off mechanism is attached. 21 is a rotatable shaft, also a part of the feeding mechanism. To the 75 cross bars 11, 11 is secured a bracket 17 one end of which is cut out to form two wings 18, 18, through which the said shaft 21 passes.

To the bracket 17 are secured two bars 15 formed with longitudinal guiding slots 16 extending from the cross bars 11 below the hanger 13 and forming fixed supporting elements for the push-off mechanism. 85

The numeral 19 denotes a pinion keyed to the shaft 21 between the wings 18 as seen in 90 Figure 5. 22 is a rack which is supported in two places on rack bars 23-23 Fig. 5, fastened to the underside of the wings 18 and on rack bars 14 secured to a hanger 13 fixed on the shaft 12. The rack is adapted to slide on the rack bars in engagement with the pinion 95 19. The rack is toothed for a suitable distance equal to the length of its stroke.

The rack carries a sheet engaging mechanism as follows, see Figure 4. The numeral 100

25 denotes a housing fastened to the rack by screws 26 so as to be adjustable lengthwise of the rack. The housing is provided with a cylindrical recess or chamber 27 and vertical side slots 28, 28. 29 is a plunger adapted to move vertically in the cylindrical recess 27. The plunger carries a shaft 30. On the shaft is mounted guide rolls 31, 31 which slide in the slots 28, and cam rolls 32, 32 outside the housing 25. To the bottom of the plunger 29 there is pinned a block 33. Springs 34, 34 act between the housing 25 and the block 33 to normally force the plunger downward. The numeral 35 denotes a sheet engaging member which is screwed fast to the block 33 and provided with an inclined sheet engaging surface 36. The arrangement is such that on the feeding stroke of the rack, to the left in Figure 1, the member 35 engages the front edge of the top sheet 36 and pushes it off the pile a short distance. Thereafter the sheet engaging member is disengaged from the sheet by a tripping mechanism.

The latter mechanism, Figure 5, comprises 25 a housing consisting of two side pieces 40, 40 joined by a transverse girder 41. The housing is adjustably secured to the aforesaid guide bars 15 by bolts 42 having heads 43 within the ways or slots 16. To each of the 30 housing side pieces 40 there is fastened a fixed tripper cam 44 having an inclined cam surface 45. The side pieces are further provided with slots 46, 46, through which extend studs 47 which carry movable tripper cams 48, 48, one adjacent each side piece 40. There are thus two cams on each side of the housing 40-41, a fixed cam and a movable cam. The movable cam is held in engagement with the fixed cam by a spring 49, the movable cam having an inclined forward cam surface 50 co-operating with the cam surface 45 on the fixed cam. In addition, each movable cam is suspended in the slot 46 by means of a spring 51. The movable cam is also provided with 55 a directing surface 53.

In describing the operation it should be understood that the shaft 21 is oscillated in synchronism with the press. Further, that in speaking of the device as a sheet push-off mechanism, it is to be understood that the sheet is pushed off the pile only a short distance to enable other sheet handling means, not shown, to engage and manipulate the sheet in the further well known operations of gripping it and conveying it to the press. Such means are, however, well known in the art and need not be described herein.

In operation, the sheets are placed on the pile elevator with the top sheet 36 at the 60 proper feeding level. In accordance with the size of the sheets, the push-off mechanism is adjusted lengthwise of the rack 22 to the position shown in Figure 1 with the sheet engaging member 35 slightly away from the 65 front edge of the sheet.

Similarly the tripping mechanism is adjusted along the guide bars 15 a distance to accord with the length of the push-off stroke.

When the press and feeder is started, the pinion 19 is moved clockwise and causes the rack to be moved towards the press from right to left in Figure 1. Consequently, the member 35 engages the edge of the top sheet and pushes it off the pile, that is to say, the top sheet is pushed a distance sufficient to separate the sheet and permit further manipulation by other sheet handling devices such as grippers.

At the end of the push off stroke, not the feeding stroke of the rack, the rollers 32 on the plunger 29 engage the fixed tripper cam 44 and run up on the inclined surface 45 thereof whereby the plunger 29 will be raised and the sheet engaging member 35 lifted away from the sheet and the push off movement ceases. The parts are so adjusted that the rollers 32 run in on the cam 44 and come to rest thereon at the end of the feeding stroke of the rack. During this movement the rollers 32 run under and lift the movable trip cams 48, which, however, are immediately pulled down again by the springs 49.

On the return stroke, the rack moves forward from left to right in Figure 1 and the rollers 32 now run upon the movable trip cams 48 and off those cams back into starting position ready to push off the next sheet. In other words, the sheet engaging member has a cycle of movement including the push-off stroke, then a lifting movement caused by the fixed tripper cam, then a return movement on the movable tripper cam and then a dropping movement back to starting position.

If for any reason the rollers 32 should be in a too high position and tend to abut the movable tripper cam instead of the fixed one, they will cause the movable cams to be lifted and run under the directing surfaces 53 and then onto the fixed cams. Hence the reason for enabling the movable tripper cam to be lifted at either end.

It will be noted that the device permits adjustment both with regards to the size of the sheet as well as regarding the movement necessary to push the sheet off the pile. For different thicknesses of sheet, a different size sheet engaging member may be used. Also, that as the sheets are moved upwards, the level of the sheet engaging member is adjusted automatically.

The device as herein described is simple in construction, easy of operation and adjustment and is readily adaptable for installation and use with existing types of automatic sheet feeding devices.

I claim:

1. A member adapted to engage the edge of the top sheet of a pile of sheets, means for operating said member to engage the edge of said sheet and move it a distance on the

pile of sheets and means for automatically disengaging said member from the sheet.

2. The combination of supporting means, a sheet engaging member slidably mounted thereon, means for operating said member a given distance, means for causing said member to engage the edge of the top sheet of a pile of sheets during a part of said movement to move said sheet along on the pile of sheets and means for automatically disengaging said member from the sheet.

3. The combination of supporting means, a sheet engaging member slidably mounted thereon, means for operating said member a given distance on said supporting means, means for causing said member to engage the edge of the top sheet of a pile of sheets to move said sheet and adjustably mounted means for disengaging said member from the said sheet at or before the end of the movement of said member.

4. In a device of the character described, the combination of supporting means, a member mounted to slide thereon, a sheet moving mechanism adjustably carried by said member and comprising a device adapted to engage the edge of the sheet and means for maintaining the same in vertically operative relation with a sheet to be moved, means for operating said slidable member to cause said sheet engaging device to engage the edge of the sheet and move the same and means carried by said supporting means for automatically interrupting the movement of the sheet engaging device to disengage it from the sheet.

5. In a device of the character described a sheet moving member having means for engaging the edge of a sheet and the surface of the sheet adjacent said edge, means for operating said sheet moving member to move the sheet, mechanism for automatically disengaging said member from contact with the sheet and means for operating said member back to starting position.

6. In a device of the character described a sheet moving member having means for engaging the edge of a sheet and the surface of the sheet adjacent said edge, means for operating said sheet moving member to move the sheet, mechanism for automatically disengaging said member from contact with the sheet and means for operating said member back to starting position, said automatic mechanism comprising means for interrupting the movement of the sheet engaging member and direct it into a different path and other means for directing the return movement of said sheet engaging member to starting position.

7. In a device of the character described, the combination of supporting means, a rack slidably supported thereon, a sheet moving member for engaging the edge and surface of a sheet to be moved adjustably secured to said rack, means for operating said rack in one

direction to cause said sheet moving member to move the sheet, automatic means for moving said sheet moving member into a different path during said movement whereby to disengage it from the sheet, means for operating said rack in the opposite direction to return the sheet moving member to starting position and means for directing said return movement into a path different from the sheet moving movement.
